(57) **CLAIM**

I claim the ornamental design for a grooved food bar, as shown and described.

DESCRIPTION

FIG. 1 is a perspective view of a grooved food bar according to the present invention, the irregular shapes represent flakes of grain on the top;

FIG. 2 is a bottom view of the grooved food bar;

FIG. 3 is a top plan view of the grooved food bar, the irregular shapes represent flakes of grain on the top;

FIG. 4 is a side elevation view of the grooved food bar; and, FIGS. 5 and 6 are end views of the grooved food bar.
